UNITED STATES PATENT OFFICE.

ROBERT W. SCOTT, OF BOSTON, MASSACHUSETTS, ASSIGNOR TO SCOTT & WILLIAMS INCORPORATED, OF CAMDEN, NEW JERSEY, A CORPORATION OF NEW JERSEY.

WEB-HOLDER MECHANISM FOR KNITTING-MACHINES.

1,169,737.

Specification of Letters Patent. Patented Jan. 25, 1916.

Application filed July 24, 1914. Serial No. 852,894.

To all whom it may concern:

Be it known that I, ROBERT W. SCOTT, a citizen of the United States, and resident of Boston, in the county of Suffolk and State 5 of Massachusetts, have invented certain new and useful Improvements in Web-Holder Mechanism for Knitting-Machines, of which the following is a specification.

My invention relates to devices for positioning independently movable web-holders with respect to the needles and needle carrier of a knitting machine.

In the accompanying drawings, Figure 1 is a vertical section through the needle carrier of a knitting machine showing the device in position; Fig. 2 is a perspective of the hold-down ring.

As shown in Letters Patent to George D. Mayo No. 726,178 dated April 21, 1903, upon 20 which my device is an improvement, needle carriers for knitting machines such as the cylinder 1 are employed in connection with an attached web-holder bed 112 carrying 25 radially sliding web-holders 105 for actuation by a cam-ring 114, the vertical position of said web-holders being determined by engagement of one of their parts with a slotted attachment of the needle cylinder 1, said web-holders being held from rising by an 30 internal collar or ring having an integral annulus taking between arms of the web-holder. I provide instead of this structure a guide-ring 297 held by screws 3 and cleats 2 taking into a groove 13 at the upper end 35 of the needle cylinder 1, thus permitting rotative adjustment and clamping of said ring 297 when desired, said ring overhanging the inner surface of said cylinder at 4, and being provided with milled slots 5 of the 40 proper gage and frequency to receive and guide the web-holders 105, whose lower surfaces rest on the surface 6 at their proper height in relation to web-holder bed 112 and the needles. The said slots are free-ended, 45 and to prevent web-holders in an inner position from rising with advancing needles,

I provide a hold-down ring 10 resting freely above the lower members of said web-holders 105. Said ring, which may be a very thin stamping of sheet steel, is provided with 50 preferably integral feet 11 bent downwardly substantially at the line of the inner circumference of said ring, and then outwardly at 12, the short projections 12 interlocking with the under surface 4 of the guide-ring 297. 55 The parts may be assembled by springing the feet 11 inward. Lint moving with the web-holders can not find lodgment against the thin outer surface of the ring 10, while the 60 openings between the feet 11 permit lint and other detritus pushed from the grooves 5 to fall within the cylinder 1. The construction of the ring 297, by the use of the ring 10, is much simplified and cheapened, while the ends of the grooves in the guide ring and 65 the top of the hold-down ring are exposed for cleaning without dismantling the machine.

What I claim is:

1. In a web-holder device for knitting machines, the combination with web-holders of a grooved guide-ring to position the web-holders with a hold-down ring lying above said web-holders having spaced feet engaging a surface of said guide ring beneath said 75 web-holders.

2. A hold-down ring for a web-holder device made as a thin annulus having depending spaced feet adapted to interlock in use 80 with a guide ring for the web-holders.

3. In a knitting machine, the combination of a needle cylinder and a slotted guide ring for movable web-holders held on said cylinder by cleats taking into an internal groove 85 in the said cylinder.

In testimony whereof, I have signed my name to this specification in the presence of two subscribing witnesses.

ROBERT W. SCOTT.
